UNITED STATES PATENT OFFICE.

PETER KAY WESTERGARD, OF ORANGEBURG, NEW YORK.

ROTARY BRUSH.

SPECIFICATION forming part of Letters Patent No. 629,225, dated July 18, 1899.

Application filed March 11, 1899. Serial No. 708,679. (No model.)

To all whom it may concern:

Be it known that I, PETER KAY WESTERGARD, of Orangeburg, in the county of Rockland and State of New York, have invented 5 a new and Improved Rotary Brush, of which the following is a full, clear, and exact description.

The object of the invention is to provide a new and improved rotary brush designed for 10 the use of barbers, stablemen, or other persons for conveniently, thoroughly, and quickly brushing the hair of human beings or animals, to remove impurities from the hair or scalp, and to gather or collect such impurities in a receiver for convenient removal from 15 time to time.

The invention consists of novel features and parts and combinations of the same, as will be fully described hereinafter and then 20 pointed out in the claims.

A practical embodiment of my invention is represented in the accompanying drawings, forming a part of this specification, in which similar characters of reference indicate corresponding parts in all the views.

Figure 1 is a side elevation of the improvement with the receiver in section. Fig. 2 is a front elevation of the same, partly in section; and Fig. 3 is a side elevation of the receiver.

The improved rotary brush is provided with a post A, preferably formed of two tubular aligned sections A' A², rigidly connected with each other by a crook A³, as plainly illustrated in Fig. 2. On the outer end of the upper section A' is adjustably held a shank B, fastened in place by a suitable set-screw B', and on the shank is mounted to turn a press-plate C, adapted to rest against the breast or other part of the user to form a support for the post when using the device, said press-plate being preferably mounted to turn loosely on a pin B², carried by the shank B.

On the tubular section A' is arranged a stud 45 D', on which is mounted to turn a bevel gear-wheel D, having a handle D² under the control of the operator to permit the latter to turn said gear-wheel. The bevel gear-wheel D is in mesh with a bevel gear-wheel E, arranged within the crook A³ and secured on a shaft F, journaled in the section A² and provided on its lower end with a bevel gear-

wheel F' in mesh with a bevel gear-wheel F², mounted to rotate loosely on a stud F³, carried by a frame G, attached to the section A² 55 and provided with a handle G', adapted to be taken hold of by the operator when using the device, as hereinafter more fully described.

On the bevel gear-wheel F² is secured or 60 formed a spur-wheel F⁴ in mesh with a pinion H', secured on the shaft H² of a rotary hair-brush H, of any approved construction, said shaft H² being journaled in suitable bearings on the frame G. On the shaft H² is hung 65 loosely a receiver or casing I for receiving the sweepings from the rotary brush H, said receiver being provided on one side with a door I', adapted to be opened for conveniently discharging the accumulated sweepings from 70 time to time.

Inside of the receiver I and at the entrance thereof is arranged an offset I² for preventing the sweepings from accidentally passing out of the receiver at the entrance-opening. 75

The device is used as follows: The operator takes hold of the handle G' with one hand and of the handle D² with the other and then rests the press-plate C against the breast or other support and swings the post A into such position as to bring the brush H in contact with the hair to be brushed. The operator now rotates the gear-wheel D, so that the rotary motion thereof is transmitted by the gear-wheel E to the shaft F and by the gear-wheels F' F² and F⁴ H' to the shaft H² and the brush H, the latter turning in the direction of the arrow a'. Now as the revolving brush is moved over the hair or skin it is evident that the hair and scalp are readily cleaned, the 80 impurities passing over the deflecting segmental portion I³ of the offset I² into the interior of the receiver to accumulate therein. As the brush is moved forward and backward over the surface to be brushed and is rotated 85 at the same time, it is evident that the casing I can swing to bring the front portion of the brush in proper contact with the hair, the casing resting on and passing over the brushed surface as the brush advances. Thus it is 90 evident that upon the brush passing over a rounded or curved surface the casing readily accommodates itself by swinging rearwardly to allow the brush to work properly by com-

ing in firm contact with the parts to be brushed. It will further be seen that by the special arrangement of the gearing the brush H is projected forwardly from the lower end 5 of the frame G and the post A, so that the solid parts do not come in contact with the parts to be brushed and the rotary brush is free to act properly on the hair under treatment.

10 Having thus fully described my invention, I claim as new and desire to secure by Letters Patent—

1. A brush mechanism comprising a post made in two sections or parts rigidly connected with each other by a crook, a shaft mounted to turn in one section, a gear-wheel journaled on the other section and in mesh with a gear-wheel on said shaft and located at the crook, a handled frame on said post-section 15 carrying the shaft, and remote from said crook, a rotary brush journaled in said frame, and a gearing connecting said brush with said shaft, substantially as shown and described.

2. A brush mechanism comprising a post 20 made in two sections or parts rigidly connected with each other by a crook, a shaft mounted to turn in one section, a gear-wheel on said shaft and located at the crook, a handled frame on said post-section carrying the shaft, 25 and remote from said crook, a rotary brush journaled in said frame, a gearing connecting said brush with said shaft, and a press-plate revolving on the outer end of the post-section carrying the gear-wheel, substantially as 30 shown and described.

3. A brush mechanism comprising a post made in two sections or parts rigidly connected with each other by a crook, a shaft mounted to turn in one section, a gear-wheel journaled 40 on the other section and in mesh with a gear-wheel on said shaft and located at the crook, a handled frame on said post-section carrying the shaft, and remote from said crook, a rotary brush journaled in said frame, a gearing 45 connecting said brush with said shaft, and a casing held on said frame and adapted to receive the sweepings from said brush, substantially as shown and described.

4. A brush mechanism comprising a post 50 made in two sections or parts rigidly connected with each other by a crook, a shaft mounted to turn in one section, a gear-wheel journaled on the other section and in mesh with a gear-wheel on said shaft and located at the crook,

a handled frame on said post-section carrying 55 the shaft, and remote from said crook, a rotary brush journaled in said frame, a gearing connecting said brush with said shaft, and a casing held on said frame and adapted to receive the sweepings from said brush, said casing being provided with an interior offset for retaining the sweepings in the casing and for guiding the sweepings into the casing, substantially as shown and described.

5. The combination with a frame, of a rev- 60 oluble brush mounted to turn in said frame and a casing mounted to swing loosely on the brush-shaft, so as to normally extend below the brush, the said casing being provided with an offset having a segmental portion for guid- 70 ing the sweepings into the casing, substantially as shown and described.

6. The combination with a frame having forwardly-projecting members at its lower end, of a revoluble brush provided with a 75 shaft mounted to turn in the forwardly-projecting members of the frame, a casing hung loosely on the brush-shaft and adapted to receive the sweepings, and an offset in said casing, substantially as shown and described. 80

7. The combination with a post and a han- 85 dled frame carried at one side of the post and having forwardly-projecting members at its lower end, of a shaft journaled in said forwardly-projecting members of the frame, a rotary brush carried by said shaft, means for rotating said brush, and a casing adapted to receive the sweepings from said brush, sub- 90 stantially as shown and described.

8. A brush mechanism, comprising a post 90 made in two sections connected with each other by a crook, a frame carried by said post and having forwardly-projecting members, a rotary brush provided with a shaft journaled in said members of the frame, a shaft mounted to turn in one of the sections of the post and provided at one end with a bevel gear-wheel located within the crook, the other end of said shaft being connected by gearing with the brush-shaft, and a bevel gear-wheel provided 100 with a handle and journaled on the other section of the post, the said bevel gear-wheel being in mesh with the bevel gear-wheel at the crook, substantially as set forth.
